UNITED STATES PATENT OFFICE.

FRANK W. HARPER, OF MIDLOTHIAN, VIRGINIA.

AIR-BRAKE COUPLING.

SPECIFICATION forming part of Letters Patent No. 639,851, dated December 26, 1899.

Application filed February 25, 1899. Serial No. 706,847. (No model.)

To all whom it may concern:

Be it known that I, FRANK W. HARPER, a citizen of the United States, residing at Midlothian, in the county of Chesterfield and State 5 of Virginia, have invented new and useful Improvements in Air-Brake Couplings, of which the following is a specification.

My invention relates to improvements in air-brake couplings, and pertains to a coupling provided with a valve for the purpose which will be fully described hereinafter.

The object of my invention is to provide a coupling having a valve with an external operating member which is engaged by the 15 acting coupling for holding it open, but which will automatically close when the coupling parts owing to the separation of one car from the other, and to provide means for locking open the valve of the coupling at the front 20 end of the cars, so that when the coupling parts, by the breaking away of the train, air will be permitted to escape and the brakes applied for stopping that part of the train which has become separated from the 25 front portion of the train, whereby accidents will be prevented, in that the two parts of the train will not collide after being broken apart, nor will the rear part of the train coast down a hill should it become separated from the 30 front portion of the train.

In the accompanying drawings, Figure 1 is a longitudinal vertical sectional view of my coupling, shewing it used in connection with the ordinary coupling. Fig. 2 is a front plan 35 view of my coupling, the interior portions being shown in dotted lines. Fig. 3 is a side elevation of my improved coupling, the valve and the rock-shaft to which it is attached being shown in dotted lines.

40 While I propose to use my coupling at both ends of the cars, in Fig. 1 I show my coupling in connection with the ordinary coupling A.

My invention pertains to a valve B, situated within the coupling C, said valve being secured to or mounted upon a rock-shaft D, which passes, as here shown, diagonally through the coupling at the lower edge thereof. One end of this shaft D extends through 45 the outer side of the coupling, and this end is provided with an operating member or

crank-arm E, whereby the valve B can be opened or closed thereby.

The outer side of the coupling is provided with a stop G and the crank E with a spring- 55 catch H, adapted to engage with opposite sides of the stop G in the manner and for a purpose which will now be described.

In the operation of my invention, Fig. 2 shows the valve-lock open by carrying the 60 spring-catch H below the stop G, so that the valve B cannot be closed by the pressure of the air within the coupling. The coupling in this figure (Fig. 2) has the valve in the position in which it will be locked when upon the 65 coupling at the front end of the car, whereby when the train in front breaks away and the two parts A and C become detached the air will be permitted to escape through the opening closed by the valve B and the brake applied to the car carrying the coupling in Fig. 70 2, and consequently to the cars in rear thereof.

In Fig. 3 the coupling is shown with the valve in the position in which it will be upon the coupling at the rear end of the car. It 75 will be noted that in this position the crank E is above the stop G, so that when the coupling parts the valve will automatically close to prevent the escape of air, and the engineer can then apply or release the brake to the 80 cars attached to his engine the same as though no break in the train had occurred, while the brakes to the cars which have broken away will be applied, in that the coupling upon the front end of the cars will have the valve B 85 locked open, as shown in Fig. 2.

The under member C of the coupling is provided at its front edge with the projecting flange I and at its rear edge with the projecting flange J, while the coating or upper member A of the coupler is provided with the projecting flanges or members K and L, which interlock with the flanges I and J. The flange K will be situated over the free end E of the crank, and as the two members of a coupling 90 are being locked together the flange K will force the crank E downward to the position shown in Fig. 3, thus locking the valve B open, so that it will not be affected by the air therein so long as the two members of the 100 coupling are united. When, however, the coupling becomes separated, the valve B is

allowed to automatically close, in that the upper member A being removed there is nothing to engage the crank E for locking the valve B open.

5 The members A and C are provided with the usual rubber gaskets *a* and *b* for making an air-tight joint between them.

Having thus described my invention, what I claim, and desire to secure by Letters Patent, is—

1. An air - brake coupling comprising a coupling having an air-passage, a rock-shaft extending therethrough at one side of the passage and carrying a laterally-projecting valve 15 adapted to close said opening, one end of the rock-shaft extending through the coupling and carrying a laterally-extending crank or actuating member, substantially as described.

2. An air - brake coupling comprising a 20 coupling having an air-passage, a rock-shaft extending therethrough at one side of the passage and carrying a laterally-projecting valve adapted to close said opening, one end of the rock-shaft extending through the coupling, a 25 lug upon the casing and a crank-arm attached to the rock-shaft and carrying a spring-catch to engage the said lug, substantially as described.

3. An air-brake coupling comprising two 30 interlocking coupling members, one member

having a swinging valve normally held closed by the air-pressure and held open when coupled by the interlocking part of the other coupling member, substantially as described.

4. An air - brake coupling comprising a 35 coupling member having an air-passage, a swinging valve having its pivot extending through the coupling and provided with a crank-arm at its outer end, said valve being normally held closed by the air-pressure, and 40 an interlocking member adapted to engage said arm and hold the valve open, substantially as described.

5. An air - brake coupling comprising a 45 coupling member having an air-passage, a rock-shaft extending diagonally through the air-passage and carrying a swinging valve, said rock-shaft having one of its ends extending through the coupling and provided with an external operating-crank in the path of 50 the interlocking part of the other coupling and held open thereby against the air-pressure, substantially as described.

In testimony whereof I have hereunto set my hand in the presence of two subscribing 55 witnesses.

FRANK W. HARPER.
